CAMOUFLAGING METHOD AND DEVICE
THEREFOR

Meldon Mitchell, New York, N. Y.

Application November 26, 1941, Serial No. 420,490

6 Claims. (Cl. 41—10)

This invention relates to a system of camouflaging particularly adapted for military use in concealing objectives from the enemy.

According to the methods of camouflaging heretofore known and used, of which the applicant has full knowledge by virtue of his experience as a camouflage expert, large sections of cord netting are employed as a conveniently pliable foundation material adapted to accommodate, through the interstices thereof, suitably intertwined strips of colored fabric or other material to give a desired color or texture effect—various sections of such netting being secured together and spread over the objects to be concealed. The work of preparing such camouflage nets and piecemealing them together is both laborious and time-consuming, being at times dangerously slow for military purposes. It is primarily within the contemplation of my invention to eliminate the shortcomings hereinabove referred to in camouflaging methods by enabling objectives, whether large or small, to be quickly and effectively camouflaged in simple manner and with a minimum of labor, to simulate any desired effect. And in this aspect of this invention, it is an important object to employ a prefabricated camouflaging unit so as to simplify and expedite the method of concealing any military objective by camouflaging means.

Briefly, the method of my invention includes the cutting of suitably disposed slits into sheets of camouflage material, applying a pull on the material in a direction transverse to the length of the slits, thereby producing a mesh-like arrangement of the material with a plurality of interstices. Sections of such material, in expanded condition, are secured together, and spread over either small or extended areas that are intended to be hidden from the enemy, the camouflage covering thus obtained being also suitably secured to the covered object.

It is within the further contemplation of this invention to eliminate independent cord netting, chicken wire and various types of wire mesh commonly employed in camouflage coverings as separate and component parts, and to employ in lieu thereof a structure capable of performing the function of said netting and wire, and forming an integral part of the covering.

In the commonly used cord netting method above referred to, the intertwined strips employed are generally of limp material, the ends dropping through the interstices rather than remaining on the upper surface of the netting, so that the intended effect is not obtained with re-

spect to an airplane observer looking down. It is another object of this invention, in one form thereof, to obviate the use of such strips and to obtain substantially the same effects heretofore obtained by properly disposed strips, by the expedient of warping the material in the region of the interstices created by the method of my invention, in a manner to be fully hereinafter described.

10 It is also within the contemplation of my invention to enable strips of the type above mentioned to be employed if deemed expedient. And in this aspect of my invention, it is a further object to enable these strips to be readily and conveniently attached to the camouflage sheets.

15 A further object of my invention is to provide a camouflage covering that could be readily and inexpensively fabricated on a production basis.

20 Where the said conventional cord netting or the like is employed, the material is generally so limp as to be difficult to handle; and because of such limpness, props or other supports are required to prevent undesired sagging and to give 25 a continuous surface effect over sharp-edged objects for concealing their outlines. It is within the further contemplation of my invention to provide, in one form thereof, camouflaging material with semi-rigid reinforcing means, and of 30 such stiffness as to be self-supportable over limited areas, yet sufficiently pliable to adequately cover and overlie irregular objects.

It is also within the contemplation of my invention to provide means to ventilate the region 35 below the camouflage covering. This is accomplished by the network of interstices producing a plurality of ventilating apertures, which also serve the purpose of peepholes. It is still a further object of my invention to reduce the effect 40 normally produced by strong gusts of wind which have a tendency to distort and blow the coverings apart. This is accomplished in this invention by the aforesaid interstices which permit the wind to pass therethrough and accordingly dissipate its force.

45 Another object of this invention is to enable camouflage coverings to be conveniently carried in rolls, either as independent units, or attached to airplanes, tanks, trucks, other vehicles and 50 stationary structures, whereby the sheets of rolled camouflage materials could thereafter be unrolled like a window shade, for immediate use.

It is a further object of this invention to provide camouflage coverings economical of space 55 while stored or being transported, and also ca-

pable of being expanded to cover extended areas.

Another object of my invention is to provide camouflaging material of such properties and in such form as to enable various materials for different effects to be readily classified, stored, sorted, indexed, identified, transported and operatively spread over the objects or areas to be hidden.

Other objects, features and advantages will appear from the drawings and the description hereinlater given.

Referring to the drawings,

Figures 1 and 2 are fragmentary plan and end views, respectively, of a sheet of material to be used as a foundation for the formation of the camouflaging covering according to this invention.

Figures 3 and 4 are fragmentary plan and end views, respectively, of the sheet of Figure 1 covered with a reinforcing material such as asphaltum.

Figure 5 is a fragmentary plan view of the sheet of Figure 3 with slits therein, according to my invention.

Figure 6 is a perspective view of the sheet of Figure 5 with camouflaging strips or ribbons attached to the regions between the slits.

Figure 7 is a fragmentary section of Figure 6 taken along line 7—7.

Figure 8 is a fragmentary perspective of another form of covering according to my invention, substantially similar to that of Figure 6 but with independent fasteners securing the strips to the sheet.

Figure 9 is a fragmentary section of Figure 8 taken substantially along line 9—9 thereof.

Figure 10 is a perspective view of the sheet of Figure 5 showing slits of a portion thereof separated according to the method of this invention, to form an extended mesh-like arrangement.

Figure 11 is an end view of Figure 10.

Figure 12 is a perspective view of the camouflage arrangement shown in Figure 6 after the slits had been separated according to the method of this invention.

Figure 13 is a perspective view of the camouflage covering of Figure 12 operatively placed over a cannon.

Figure 14 is a view similar to Figure 5, showing granules of camouflage material for producing a predetermined surface effect, according to a modified form of this invention.

Figure 15 is an end view of Figure 14.

Figure 16 is a plan view of Figure 14 in expanded condition.

Figure 17 is a perspective of a roll of camouflage material according to my invention, showing a convenient way in which various types and classes of camouflage material can be arranged for storing, assorting and transporting.

Figure 18 is a perspective view of a cylindrical tube containing therein a roll of camouflage material according to my invention.

Figure 19 is a fragmentary perspective showing the manner of attachment of the camouflage material to the retaining strip within the tube.

Figure 20 is a perspective view of an airplane showing several containers like that of Figure 18 secured in place.

Figure 21 is a perspective view of the airplane of Figure 20 with the camouflage sheets rolled downwardly from the containers.

Figure 22 is an enlarged fragmentary perspective of the airplane of Figure 21, with adjacent camouflage strips secured together after

being spread apart according to the method of this invention.

Figure 23 is an enlarged fragmentary perspective showing the means of attachment of two adjacent camouflage sections.

Figure 24 is a fragmentary perspective of a modified form of the camouflaging sheet of my invention.

In the preferred form of my invention, I employ a sheet of pliable material 28 as a foundation for the covering, this material being either a textile fabric, laminated paper or any other suitable pliable material. In one method of practicing my invention, the sheeting 28 has applied thereto a coating of reinforcing binding material, such as asphaltum or any other suitable material adapted to cool from a molten mass to become dry and semi-rigid. Figures 3 and 4 show a coating 26 of asphaltum applied to the surface of sheet 28, thereby producing a reinforced semi-rigid sheet which is self-supportable over a limited extent and yet bendable. A plurality of slits 27 are then formed into the reinforced sheet 28 by any suitable cutting means, such as a conventional cutting die. In the preferred arrangement, the slits are disposed in parallel rows in staggered relation, alternate rows being identically disposed with corresponding slits in horizontal alignment.

If it is desired to employ camouflage strips or ribbons such as are now used in conjunction with cord netting, the said strips 29 can be applied to the portions of sheet 28 between the slits 27, as is indicated in Figures 6 and 7. The said strips 29 can be applied either adhesively, or by means of fasteners 30 as indicated in Figures 8 and 9. If asphaltum is employed as the reinforcing material, the strips 29 can be attached before the asphaltum has cooled and while it is still sticky so that no independent adhesive or fastening means need be employed.

By referring to Figure 10, it will be seen that when opposite pulls are applied in directions A and B, transverse to the longitudinal extent of the slits, the slits will be separated to form a plurality of apertures 31, these apertures constituting in effect interstices of a mesh-like or netted arrangement resulting from the aforesaid pull. The entire region of the sheet 28 containing the mesh-like arrangement is spread to expanded proportions by such a pull, and such region is also somewhat distorted due to the warping of the portions of material 28 surrounding each of the interstices 31 out of the plane of the sheet. By referring to Figure 11 it will be seen that the region 32 is considerably thicker than the region 33 representing a single sheet of the covering material where the slits have not been separated. If the slits are made a trifle shorter, and farther apart, the distortion will be correspondingly greater, thereby serving the functions of camouflage strips such as those identified by the reference numeral 29, under certain conditions. Not only would the use of camouflage strips be eliminated with such a construction, but the use of all surface texture elements like granules, sand, etc., as well, particularly when the surface of the material is prepared with an irregular pattern of some dull camouflage color pigment. This would produce a varied irregular surface pattern composed of highlights, and a multiplicity of shades to blend with the terrain in a very deceptive manner.

It is within the contemplation of my invention to employ the slitted sheeting 28 with vari-

ous types of surface effects, either a flat color pigment applied to the surface, or strips or ribbons 28 of camouflage material as shown in Figure 12, or special types of camouflage texture particles 34 (Figures 14 and 15) made of granules of cork, bark, sisal, paper, sand or other suitable elements. The last mentioned type is illustrated in Figure 16 when in its extended condition, and the ribbon type is illustrated in similar condition in Figure 12.

When a sheet of suitably surfaced sheeting 28, in its expanded condition, is applied to an object to be concealed from the enemy, such as the gun 38, the reinforced semi-stiff material 28 is self-supportable over limited areas. This is a distinct advantage over the limp cord netting conventionally used which requires special structural elements to prop up different sections of the camouflage covering. Due to the pliability of the material, it is readily formed into creases, folds and elevations with the least amount of effort to simulate ground conditions and to give no suspicion of the underlying objectives. Should it be desired to make adjustments in the covering, it will not be necessary to remove structural props, but merely to manipulate the covering according to requirements. Furthermore, the interstices 31 enable observations to be made, and serve to admit air for ventilation, which has always been considered extremely necessary for the men operating therebeneath. The interstices also serve to reduce the wind resistance, thereby enabling this structure to stand up in windy weather much more readily than the solid type of camouflage.

By arranging and cutting sheets 28, while in their contracted or unextended conditions, to predetermined sizes, they can be readily formed into rolls 38, and thereafter conveniently sorted and labelled such as by the label 37, according to the surface characteristics or ground typography intended to be simulated. By properly indexing such rolls Army officers can at any time, by referring to a camouflage manual specially prepared for the purpose, order the desired type of camouflaging material for use in any terrain, merely by designating the type required by a suitable number or other means of identification.

The adaptability of sections of completed camouflage material made according to this invention for use in rolls renders such material suitable for many important military applications. For example, a roll of this type of camouflage material 38 may be placed within a cylindrical container 39 (Fig. 18) so that the lowermost portion extends from the slot 40. The roll may be disposed over a yieldably mounted shaft 41 similar to that employed in conventional window shades, the details of which are not herein described as the structure is well known in the art. The upper portion of sheet 28 is preferably detachably secured to the retaining strip 42 fastened to said shaft 41, the detachable fastener 43 being one method by which the sheet 28 and strip 42 are connected. It is of course understood that other means of supporting the sheet 28 may be employed within the scope of this invention and with the same force and effect as by the specific means illustrated.

The tubes 39 can be secured to any object intended to be concealed from the enemy, such as an airplane, tank, truck, hangar, building or other structure. When applied to an airplane, a number of tubes 39 may be secured to the 75

upper portions and on both sides thereof, or to such other regions where they would be least discernible and would constitute a minimum impediment. When the airplane is grounded and ready to be camouflaged, the sheets 28 are pulled down from the tubes, in the manner indicated in Figure 21. It will be noted that in this condition the slits 44 are closed. Thereafter the fasteners 43 are removed, and each sheet 28 stretched laterally, the upper ends being attached to the hooks 45 at the top of the structure. The lateral edges of adjacent sheets are also detachably secured together by the ring fasteners 46, as indicated in Figures 22 and 23. In this manner the originally relatively narrow sheets are spread out over an extended area to provide a continuous camouflage covering for the entire airplane. To return the camouflage sheets to their containers, the fasteners 43 are removed, each sheet detached from hooks 45, a pull applied in the longitudinal direction of the slits, whereby the netted material is contracted and the slits closed; and then the sheet is attached to the retaining strip 42 and the entire section operatively retracted through slot 40.

The modification shown in Figure 24 is intended to prolong the useful life of camouflaging sheets of my invention. The slits 47 have enlarged terminals 48, preferably in the form of circular apertures which prevent a tearing of the material at the ends of the slits upon an operative opening of the slits. Where the slit is cut in a straight line, there might be a tendency to rip open the material in the direction of said line.

It is thus apparent that by the system of camouflaging herein described, suitable camouflage materials can be economically prepared in sheets by production methods, and relatively narrow sections of these sheets in predetermined lengths can be stored and transported in compact form. These sheets can be then expanded to cover areas several times their original extent, and applied to the objective to be concealed with a speed consistent with modern military requirements. And when operatively applied, the resulting covering offers not only the desired camouflaging effect, but also ventilation and visibility for the men beneath the covering. Furthermore, it lends itself readily to adjustments and changes in arrangement without the use of structural props, and can to a very considerable degree remain unaffected by atmospheric disturbances.

It is of course understood that other additional forms and adaptations of the devices, materials and method can be employed beyond and in addition to those hereinbefore described, all within the scope of the appended claims.

What I claim is:

60 1. In a method of military camouflaging of an objective with sheet material, the steps of providing a foundation sheet of pliable material, stiffening said foundation material a predetermined amount by reinforcing it a predetermined amount along the entire extent thereof whereby the pliability will be decreased without rendering it unbendable, cutting slits in a section of said reinforced material at predetermined intervals, separating said slits to form a plurality of interstices in the material, and applying said section over the objective.

65 2. In a method of military camouflaging of an objective with sheet material, the steps of applying asphaltum to a foundation sheet of pliable material whereby the sheet will be stiffened

without becoming unbendable, cutting slits in a section of said stiffened material at predetermined intervals, separating said slits to form a plurality of interstices in the material, and applying said section over the objective.

3. In a method of military camouflaging of an objective with sheet material, the steps of applying to a foundation sheet of pliable material a molten mass of reinforcing material adapted to become dry and semi-rigid upon cooling, cutting slits in a section of said material at predetermined intervals, attaching camouflaging elements of predetermined characteristics to said section at the regions between the slits and upon said reinforcing material before it has dried, whereby said elements will adhere to the said section upon a drying of said reinforcing material, separating said slits to form a plurality of interstices in the material, and applying said section over the objective.

4. In a military camouflaging device, a camouflage covering sheet of pliable material, at least one layer of reinforcing material applied over said sheet, said reinforcing material being of greater stiffness than said pliable sheet whereby the combined sheet and layer will be self-

supportable over a limited extent and yet bendable, and a plurality of slits at predetermined intervals in said sheet, said slits being adapted to be separated to form interstices in the material.

5. In a military camouflaging device, a camouflage covering sheet of pliable material, at least one layer of asphaltum applied over said sheet, and a plurality of slits at predetermined intervals in said sheet, said slits being adapted to be separated to form interstices in the material.

6. In a military camouflaging device, a camouflage covering sheet of pliable material, at least one layer of reinforcing material applied over said sheet, said reinforcing material being of greater stiffness than said pliable sheet whereby the combined sheet and layer will be self-supportable over a limited extent and yet bendable, a plurality of slits at predetermined intervals in said sheet, said slits being adapted to be separated to form interstices in the material, and a plurality of camouflage elements secured to the surface of said sheet between the said slits thereof.

MELDON MITCHELL.
